United States Patent Office

Des. 217,896
Patented June 30, 1970

217,896

WRENCH OR SIMILAR ARTICLE

James M. Sexauer, White Plains, N.Y., assignor to J. A. Sexauer Mfg. Co., Inc., White Plains, N.Y., a corporation of New York

Filed June 20, 1969, Ser. No. 17,787

Term of patent 14 years

Int. Cl. D8—02

U.S. Cl. D8—29

FIG. 1 is a side view of a wrench or similar article, showing my new design;

FIG. 2 is an end view thereof;

FIG. 3 is another end view thereof;

FIG. 4 is a perspective view of another embodiment of the present invention;

FIG. 5 is a perspective view of another embodiment of the present invention;

FIG. 6 is a perspective view of another embodiment of the present invention;

FIG. 7 is a side elevational view of another embodiment of the present invention;

FIG. 8 is an end view thereof;

FIG. 9 is another end view thereof;

FIG. 10 is a perspective view of another embodiment of the present invention;

FIG. 11 is a perspective view of another embodiment of the present invention; and

FIG. 12 is a perspective view of another embodiment of the present invention.

I claim:

The ornamental design for a wrench or similar article, substantially as shown.
